UNITED STATES PATENT OFFICE.

GILBERT W. GOODRIDGE, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

REFILLABLE CARTRIDGE-FUSE.

1,179,174.

Specification of Letters Patent.

Patented Apr. 11, 1916.

Application filed November 25, 1914. Serial No. 873,932.

To all whom it may concern:

Be it known that I, GILBERT W. GOODRIDGE, a citizen of the United States of America, and residing at Bridgeport, in the county of Fairfield and State of Connecticut, have invented a certain new and useful Improvement in Refillable Cartridge-Fuses, of which the following is a specification.

10 My invention relates to refillable cartridge fuses and the object of my invention is to provide a device of this character which is economical to manufacture and efficient in service.

15 In the accompanying drawing, Figure 1 is a longitudinal section through a cartridge fuse in which my invention is embodied in one form; Fig. 2 is a similar view at right angles to Fig. 1; Fig. 3 is a plan of the fuse blank; Fig. 4 is a perspective of one of the bridge pieces; and Fig. 5 is a perspective of one of the caps.

20 As here shown, the present fuse comprises a cylindrical casing or shell 10 of insulating material such as paper or fiber. Within each end of the shell, I arrange a transverse bridge piece or strap 11 which is rigidly secured in any suitable manner, as by the rivet 12, and preferably in such position 25 that its outer face is substantially flush with the end of the shell 10. Spaces 13 on each side of the bridge piece permit the end 14 of the fuse 15 to be passed beyond the bridge piece and angled across the outer 30 face of the latter. A slot 16 is preferably formed in the end of the fuse to register with the threaded hole 17 in the bridge piece. A closure cap 18 spun or struck from sheet metal, fits over the end of the shell and its 35 end diaphragm 19 is perforated at 20 in register with the hole 17 in the bridge piece, both holes 17 and 20 being preferably axial to the fuse. Vent holes 21 may also be formed in the diaphragm. The screw 22 40 passes through the hole 20 in the cap diaphragm and threads into the hole 17 in the bridge piece, thus not only securing the cap in position, but also firmly clamping the fuse end between the cap diaphragm and 45 the bridge piece.

50 The central portion of the diaphragm 19, to approximately the internal diameter of the shell 10, is preferably inwardly offset so that it may enter within the shell in case 55 the bridge piece is not flush with the end of

the latter (see left hand end Fig. 1). In this case the end of the shell enters the channel 23 thus afforded for its reception.

5 The assembly of the device is obvious. The caps 18 being removed from each end of the shell, the fuse 15 is inserted through the spaces 13 to the sides of the bridge pieces and the ends 14 angled over the latter, so that the slots 16, if used, register with the threaded holes 17 in the bridge pieces. The 65 fuse may be passed through spaces on the same side of the bridge pieces or on opposite sides as shown. The caps 18 are then readjusted and the screws 22 inserted and tightened thus clamping the caps against the fuse 70 ends and establishing electrical connection between the same. The caps serve as fuse terminals in well known manner.

I claim as my invention:

1. A refillable cartridge fuse having a 75 shell of insulating material, a U-shaped transverse bridge piece fitting within one end of said shell and riveted permanently thereto, a cap fitting freely over the end of the shell and provided with a perforated 80 closure diaphragm, a fuse extending longitudinally within the shell and having an end bent over the outer end of the bridge piece and a clamping screw passing through the cap diaphragm and threaded into the 85 bridge piece and serving not only to hold the cap in position but also to clamp the bent over end of the fuse between the cap diaphragm and bridge piece, substantially 90 as described.

2. A refillable cartridge fuse having a shell of insulating material, a transverse bridge piece fitting within one end of said shell and riveted permanently thereto, said bridge piece being tapped on the axis of the shell, a cap fitting freely over the end of the shell and provided with a closure diaphragm apertured in line with the tap in said bridge piece, a fuse extending longitudinally within the shell and having an end bent over the outer end of the bridge piece and a clamping screw passing through the cap diaphragm and threading into the tap in the bridge piece and serving not only to hold the cap in position but also to clamp the bent-over end of the fuse between the cap diaphragm and bridge piece, substantially 105 as described.

3. A refillable cartridge fuse having a shell of insulating material, a transverse 110

bridge piece fitting within one end of said shell and riveted permanently thereto, said bridge piece being tapped on the axis of the shell, a cap fitting freely over the end of the shell and provided with a closure diaphragm apertured in line with the tap in said bridge piece, a fuse extending longitudinally within the shell and having an end bent over the outer end of the bridge piece and apertured in register with the tap in the latter and a clamping screw passing through the cap diaphragm and aperture in the fuse end and threading into the tap in

bridge piece and serving not only to hold the cap in position but also to clamp the bent over end of the fuse between the cap diaphragm and bridge piece, substantially as described.

In testimony whereof I have signed my name to this specification in the presence of two subscribing witnesses.

GILBERT W. GOODRIDGE.
